UNITED STATES PATENT OFFICE.

HENRY ALLEN AVERY, OTTO PETERMANN, AND EDWIN L. HARMON, OF GROTON, NEW YORK, ASSIGNORS, BY MESNE ASSIGNMENTS, TO L C SMITH & CORONA TYPE-WRITERS INC., OF SYRACUSE, NEW YORK, A CORPORATION OF NEW YORK.

TYPEWRITING MACHINE.

Application filed November 13, 1926. Serial No. 148,257.

This invention relates to improvements in typewriting machines, and more particularly to platen carriage feed mechanism for such machines.

5 The invention has for its principal objects to provide an improved escapement mechanism; to provide an efficient rotary escapement mechanism of simple and inexpensive construction; to provide means consisting of 10 a minimum number of parts, and of light and inexpensive construction, whereby the carriage may be fed step-by-step to the right and to the left and may be given a continuous or running movement to the right and to the 15 left; to provide a combined releasing and controlling means for the dog rocker of an escapement; to provide efficient means for controlling the throw of the dog rocker; to provide simple and light dog-rocker-tripping 20 means for releasing a carriage the letter-feed movement of which is controlled by a rotary escapement; to provide an escapement operable independently from a type-bar actuated universal bar and a space bar; to provide a 25 rotary escapement which may be readily assembled and disassembled; and to provide carriage feeding and releasing means especially adapted for use in a low and compact portable typewriting machine having a 30 shifting platen carriage.

To the above and other ends, which will hereinafter appear, the invention consists in the features of construction, arrangements of parts, and combinations of elements particularly pointed out in the claims, and more fully hereinafter described.

In the drawings, wherein the preferred embodiment of the invention is illustrated.

Fig. 1 is a vertical longitudinal sectional view of a portable three-quarter strike typewriter in which the improvements are embodied, the parts being in normal position;

Fig. 2 a detail view showing parts of the case shift means in perspective;

Fig. 3 a detail sectional view of part of the case shift means;

Fig. 4 a rear view of the machine on a reduced scale, with certain parts broken away, and as seen at an angle perpendicular to the 50 inclined partition wall of the main frame;

Fig. 5 a fragmentary perspective view of the machine with the parts in normal position;

Fig. 6 a fragmentary plan view of the machine with the platen carriage removed; 55

Fig. 7 a vertical sectional view with the parts positioned as at the end of a printing stroke of a type bar;

Fig. 8 a vertical sectional view, showing the escapement released; 60

Fig. 9 a bottom plan view of the escapement device with the parts in normal position;

Fig. 10 a section on the line 10—10 of Fig. 9;

Fig. 11 a bottom plan view of the escapement device with the parts positioned as in Fig. 7; 65

Fig. 12 a section on the line 12—12 of Fig. 11;

Fig. 13 a bottom plan view showing the 70 action of the escapement wheel and loose dog during a continuous return movement of the carriage, or a back-spacing movement of the carriage by the back-space key mechanism;

Fig. 14 a section on the line 14—14 of Fig. 13; 75

Fig. 15 a view of the escapement device as seen from the rear at an angle perpendicular to the plane of case-shift movement of the shift frame;

Fig. 16 a detail perspective view showing the independent operating connections of the space bar and universal bar with the dog rocker; and 80

Fig. 17 a detail view showing parts of the escapement mechanism in perspective and detached. 85

The improvements have been illustrated in connection with a portable three-quarter strike typewriting machine having a main frame, a type-bar action, a shift frame, and a platen carriage mounted on the shift frame, all constructed and arranged as in the well known Corona Four typewriting machine, and as disclosed in the application of A. B. 90 Ely and E. L. Harmon, Serial No. 66,000, filed October 31, 1925. 95

The main frame comprises a front wall 10, a back wall 11, side walls 12, and a transverse partition wall 13. Wall 13 lies in an upwardly and rearwardly inclined plane in the rear portion of the main frame with the lower edge of the wall above the level of the lower edges of the remaining frame walls. A type bar segment 14 lies in a plane parallel with 100 wall 13 and is held to the front face of said 105

- wall by fastening screws with the usual curved pivot wire 16 for the type bars lying in a plane parallel with the plane of said wall. The type bars 17 are fulcrumed on wire 16
- 5 to strike on the upper front quarter of the platen 18. The character key levers 19 are fulcrumed at their rear ends on a pivot wire 20 which is led to a fulcrum plate 21 secured to the rear face of wall 13 by fastening screws.
- 10 The key levers 19 extend down behind wall 13 from wire 20, and then forward under said wall to the front part of the frame, and are guided in a comb 22 held to the frame. The connection between each type bar and its as-
- 15 sociated key lever comprises a bell-crank lever 23, fulcrumed in a sub-lever segment 24 held to the main frame, and links 25 and 26 connecting said bell-crank at its opposite ends with the type-bar heel and key lever, re-
- 20 spectively.

The shift frame comprises a rearwardly and downwardly inclined carriage bed 28 having a pair of downwardly and forwardly inclined guiding members 29 depending

25 therefrom adjacent opposite sides of the machine and located between a pair of similarly inclined guide members 31 held to the main frame side walls 12. Members 29 are connected adjacent their lower ends by a trans-

30 verse brace rod 30.

The platen carriage 27 is mounted on bed 28 in a rearwardly tilted position to travel transversely of the machine on forward ball bearings 1 and a rear roller bearing 4. Bearings

35 1 are confined between raceway members 2 and 3 held to the carriage and bed, respectively, while roller 4 is journalled on a stub shaft 5 (held to a sheet metal bar 6 at a point substantially midway the ends of the carriage) and travels on the upper edge of a second sheet metal bar or rail 8. Bar 6 is detachably held against the rear edge of the carriage base plate by screws 7, and bar 8 is detachably held against the rear edge of

40 bed 28 by screws 9.

The platen carriage 27 supports platen 18 above and in rear of the type bar pivots, and the carriage and its bed 28 overlie the space between frame walls 11 and 13 while guide

45 members 29 and 31 are located substantially entirely in the space between said walls and the connecting portions of side walls 12. Members 29 and 31 are provided with co-operating races 32 and 32^a, respectively, in

50 which travel ball bearings 32^b, said members, races and bearing balls being arranged to guide the shift frame to shift in a plane parallel with the planes of wall 13 and segment 14.

The shift frame is shiftable upward and

60 rearward from lower to upper case position by either of two shift key levers 33 having forked rear ends embracing studs 34 on the forward ends of side arms 35 of a shift torsion frame comprising said arms and a rock shaft

65 36 to which the arms are held. Shaft 36 is

journalled at its ends on side walls 12 of the frame and lies between wall 11 and the lower part of the shift frame close to the bottom of the main frame. Studs 34 are engaged in rearwardly and downwardly inclined slots

70 37 in guide member 29 of the shift frame. Shift levers 33 extend through slots in wall 13 and are fulcrumed on transverse pivot screws 38 held to a pair of brackets 39 (secured to frame walls 12), which brackets also support a curved and rearwardly inclined rest 40 for the heads of the type bars. The lower case position of the shift frame is determined by engagement of stops 41 on members 29 with stop screws 42 on a pair of brackets 43 held to frame walls 12, while the upper case position of the shift frame is determined by engagement of stop screws 44 on members 29 with stops 45 on brackets 43. The foregoing parts are all constructed and arranged as in the machine and application

75 above referred to.

In the improved machine, herein shown, frame 35—36 is arranged to counterbalance the shift frame by connecting lugs 46 on arms 35 with arms 48 on brackets 43 by a pair of counterbalancing springs 47. The present machine is provided with ribbon vibrating, ribbon feeding, and ribbon reversing means (not shown) all mounted to shift with the shift frame, and all operated from an actuator comprising a rock shaft 64. The construction and mounting of the ribbon mechanism, and the mode of operation thereof from said rock shaft, are disclosed in the application of Avery, Petermann and Harmon, Serial No. 148,255, filed November 13, 1926.

The ribbon mechanism actuator or rock shaft 64 is journalled on the main frame and extends transversely of the machine under

105 the lower edge of wall 13 above the key levers 19. Said actuator 64 is operable, together with an actuator 166 for the dog rocker of the escapement mechanism, from a single type-bar-actuated universal bar 49, and the dog

110 rocker of the escapement is operable independently of said universal bar and actuators 166 and 64 by an actuator 178 operated by the space bar 167 of the machine.

The arcuate sheet metal universal bar 49 is located between wall 13 and segment 14 and vibrates in a recess 15 in the segment, said universal bar lying in a plane parallel with wall 13 and being supported to vibrate in a path substantially perpendicular to the planes of wall 13 and segment 14 and the plane in which the curved pivot wire 16 for the type bars lies. The universal bar is carried at the forward ends of a pair of two-part sheet metal side arms comprising front sections 50 and 51 (preferably formed integrally with the arcuate universal bar) and rear sections 50^a and 51^a. The side arms extend rearward and downward from the universal bar through wall 13 and plate 21, which are pro-

115

120

125

130

vided with openings 52 and 53 for the arm sections 50 and 51. The front portions of arm sections 50^a and 51^a are rigidly but detachably held to the right hand side faces of 5 the rear portions of sections 50 and 51, in rear of wall 13 and plate 21, by pairs of clamping screws 54 threaded into sections 50 and 51. The side arms extend rearward and downward through the shift frame and shift 10 torsion frame, between the guides 29 and between the rock arms 35, and between the bed 28 and brace rod 30, to a point adjacent wall 11 and the base line of the main frame. Sections 50^a and 51^a of the side arms are offset 15 laterally inward at the rear ends of sections 50 and 51 and are provided with longitudinal slots 50^b and 51^b in their offset rear portions extending perpendicular to the planes of wall 13 and segment 14. These slots are open 20 at their rear ends and correspond in width with the diameter of rock shaft 36, which shaft extends through said slots to form a support cooperating with the slots to guide the universal bar side arms to reciprocate end- 25 wise. A transverse bridge or spacer bar 55, formed integrally with section 50^a forward of shaft 36, abuts the inner face of section 51^a. The side arms are supported and guided intermediate the universal bar 49 and shaft 36 30 on fore-and-aft rockable supporting arms 56 and 57 which are rigidly held at their lower ends to a short transverse rock shaft 58. Shaft 58 has trunnions 58^a journaled on the inner ends of horizontal bearing screws 59 35 threaded through the rear ends of a pair of arms 21^a and 21^b which are formed integrally with fulcrum plate 21 and extend rearward and downward to a point forward of rod 30 and close to the base line of the main frame. 40 Arms 56 and 57 extend upward and rearward, forward of rod 30, at a slightly less angle from the vertical than wall 13 and the shift frame, and have pivot holes in their upper ends in which are engaged the reduced 45 inner ends of pivot studs 61, the reduced outer ends of the studs being swaged in apertures in the side arm sections 50 and 51, respectively, forward of side arm sections 50^a and 51^a. 50 Forward movement of the universal bar 49 is limited by engagement of said bar with the front wall of recess 15 in the segment 14, and rearward movement thereof is limited by engagement of an adjustable overthrow-pre- 55 venting stop with rock shaft 36. This stop comprises a fore-and-aft bendable integral finger 62 on side arm section 51, depending from the top wall of slot 51^b, and having a rubber cushioning sleeve 63 frictionally held 60 thereon. Stop 62-63 is adjusted to engage shaft 36 only after a full printing movement of a type bar, the type bars 17 being provided adjacent their pivots with lugs 17^a for engaging the front edge of the universal bar and 65 moving the universal bar rearward, and being

also preferably provided with lugs 17^b for engaging an anvil face 14^a on segment 14. The extent of throw of the universal bar and rock arms 56 and 57 are such that pivot studs 61 swing between points substantially equal distances at opposite sides of a plane through the axis of shaft 58 parallel with wall 13. The described arrangement and movement of arms 56 and 57, together with the described arrangement of slots 50^b and 51^b in the side arms and of shaft 36, provides for supporting and guiding universal bar 49 to vibrate obliquely to the horizontal plane of the machine in a path substantially perpendicular to the inclined plane of the segment 14 and its type 70 pivot wire 16.

A rock arm 68 depends from the ribbon mechanism actuating shaft 64 at a point substantially in the fore-and-aft vertical plane of side arm 51-51^a of universal bar 49. This rock arm extends down between adjacent key levers of the machine to a point below the key levers and close to the base line of the main frame. A fore-and-aft extending rigid wire link 69 connects the lower end of arm 68 with the lower end of an arm 70 which is formed integrally with side arm section 51^a and extends downward from the forward end of said section to a point below the level of rock shaft 58 and between said shaft and rod 30. It will be obvious that upon actuation of the universal bar the ribbon mechanism actuating shaft 64 will be rocked by link 69 and arms 68 and 70 to actuate the ribbon mechanism. 90

The universal bar and shaft 64 are restored to, and yieldably held in, normal position by a return spring 74. Spring 74 is connected at its rear end with a rock arm 73 depending from shaft 64 and is connected at its forward end with a spring anchor bar 75. This anchor bar extends transversely of the machine and is supported at its ends in slots 76 in arms 43^a of brackets 43, said bracket arms extending forward under wall 13 and supporting bar 75 below the key levers 19 and forward of the rear upturned end portions of the key levers. Return springs 77 for key levers 19 are connected at their rear ends with the key levers and at their forward ends with the bar 75. 100

The actuator 166 for the escapement dog rocker comprises a shoe or tappet formed on the rear end of side arm section 50 and projecting rearward beyond the rear end of the outwardly offset forward portion of side arm section 50^a of the universal-bar-carrying means. The rear contact edge of said tappet or shoe 166 inclines upward and rearward in a plane parallel with wall 13 and the path of case-shift movement of the shift frame and is sufficiently long to actuate the dog rocker in both case positions of the shift frame. 120

In order that the dog rocker (hereinafter described) may be actuated from the space bar, independently of actuation of the rib- 130

bon mechanism and the universal bar, the following means are provided. Space bar 167 is supported forward of the character keys on the forward ends of a pair of sheet metal 5 rock arms 168 which are fixed at their rear ends on a transverse rock shaft 169 having trunnions 170 at its ends journalled in forwardly extending ears 171 punched up from the comb member 22. A rock arm 172 fixed 10 on said shaft, extends downward and forward in front of the comb 22 and is pivotally connected at its lower end with the front end of a fore-and-aft extending tappet bar 174 by a transverse pivot screw 173. Tappet bar 174 15 extends rearwardly through a guide slot 175 in comb 22 and then under sub-lever segment 24, rock shaft 64 and wall 13. Said bar extends upward behind wall 13 and then diagonally rearward and downward along the 20 outer side of side arm section 50 of the vibratory supporting means for universal bar 49. This inclined rear portion of the bar 174 is formed with a guide slot 176 extending substantially perpendicular to wall 13 and in 25 which is engaged the reduced shank portion 177^a of a supporting and guiding stud 177 held to, and extending horizontally outward from the upper part of rock arm 56 on shaft 58. The independent actuator 178 for the dog 30 rocker comprises a tappet or shoe formed on the rear end of bar 174 and located alongside of tappet 166. The rear contact edge of tappet 178 is parallel with wall 13 and the path of case-shift movement of the shift 35 frame and is made sufficiently long to actuate the dog rocker in both case positions of the shift frame. Tappet 166 is preferably arranged slightly forward of tappet 178 so that the dog rocker may be actuated by a short dip 40 of the space bar and the dog rocker will be rocked and may return to normal position during a minimum final part of the printing stroke and initial part of the return stroke of a type bar. This arrangement also provides 45 for utilizing the full throw of the universal bar to actuate the ribbon mechanism.

Bar 174 and space bar 167 are returned, and normally yieldably held in the position shown in the drawings, by a coil spring 179 which 50 is connected at its rear end with bar 174 and at its forward end with anchor bar 75. An upstanding stop lug 180, formed on bar 174, engages the rear face of comb 22 to limit return movement of bar 174 and the space bar 55 167. Depression of the space bar and rearward movement of tappet bar 174 are limited by engagement of stop lugs 181 on the space-bar-supporting arms 168 with the upper ends of the forward pair of the four rubber sup- 60 porting feet 182 which are attached to the main frame, as in the Corona Four machine and as disclosed in said application of Ely and Harmon above referred to.

With the above described arrangement, 65 the tappet bar 174 (while supported and

guided in part on a swinging part of the supporting and guiding means for universal bar 49) is operable without moving the universal bar or the ribbon actuator, and the universal bar is operable without actuating 70 the tappet bar. Rocker arms 172 and 56, and stud 177 and slot 176, support and guide bar 174 so that tappet 178 moves rearward and downward, when the space bar is depressed, with its contact edge always substantially 75 parallel with wall 13 and the path of shift of the shift frame, the pivot 173 moving rearward and downward and slot 176 extending rearward and downward.

A sheet metal dog-rocker-supporting bracket 80 has its relatively short and narrow flat main body part detachably held against the bottom face of the carriage bed 28, substantially midway the ends of the bed, and is formed with a pair of integral side 80 arms 81 and 82 bent down at the ends of the bracket and extending rearward and downward parallel with each other to points beyond the rear edges of the body of the bracket and the carriage bed and within the main frame above rock shaft 36. The arms 81 and 82 lie flatwise in fore-and-aft extending vertical planes and do not extend down within the vibratory supporting and guiding means for the universal bar. A steel bearing bushing 83 extends through a central aperture 84 in the body part of bracket 80 perpendicular to said body part and the carriage bed, and has an intermediate circumferential shoulder portion 83^a thereof swaged tightly in said 95 aperture, so that when the bushing is once assembled on the bracket it becomes in effect a permanent part of the bracket.

A feed pinion 85 is formed integrally with a pinion shaft 86 at the upper end of the shaft. Shaft 86 extends through and is journalled in bushing 83, and is formed with a circumferential collar 86^a below the feed pinion seated on the upper end of the bushing. The shaft is formed with a threaded axial bore 87 in its lower portion and the projecting lower end of shaft 86 below bushing 83 is cut away at diametrically opposite points to form two integral diametrically opposite key portions 86^b extending outward 100 from said bore and engaged in correspondingly arranged radial notches or slots 88^a at opposite sides of a central aperture 88 in a toothed sheet metal escapement wheel 89. Said keys and notches are so arranged with 105 relation to the teeth of the feed pinion and escapement wheel, respectively, that when the wheel is seated on the reduced end of the pinion shaft the teeth of the wheel and pinion will be in proper relation with each other. The wheel corresponds in thickness with the length of the projecting lower end of shaft 86 so that its upper face loosely engages the 110 lower end of the bushing. A retaining screw 90 is passed upward through a washer 115

91 (which abuts the lower face of the wheel and the lower end of shaft 86) and the central aperture in wheel 89 and is screwed into the threaded bore 87 in the shaft 86. It will 5 be observed that collar 86^a and the top face of wheel 89 cooperate with the ends of bushing 83 to prevent vertical play of the feed pinion and its shaft and the escapement wheel, and that the feed pinion and its shaft 10 and the escapement wheel may be readily assembled on the bracket and readily removed therefrom. The feed pinion, when the bracket is attached to the bed 28 by the pair 15 of screws 92 (which are passed through holes 80^a in bracket 80 and are screwed upward into threaded apertures 92^a in the bed located at predetermined points) meshes with a feed rack 93 on the carriage 27 and is located between the carriage bed and the base 20 plate of the carriage. This feed rack comprises an integral flange extending upward and forward from the lower edge of the bearing-roller-carrying bar 6, before described, between the base plate of the carriage 25 27 and the carriage bed 28, parallel with the bed, and formed with teeth along its forward edge. The carriage bed is provided with an opening 94 through which the upper end of bushing 83 extends and through which 30 the feed pinion is adapted to pass in assembling and disassembling the escapement.

A dog rocker, together with a pair of dogs and controlling means for the dog rocker and for the pivoted or feeding dog, are also 35 adapted to be assembled on bracket 80, and these parts adjusted to properly coact with escapement wheel 89, before the bracket is attached to the bed. The dog rocker 95 is formed of sheet metal and its main body part 40 comprises a sheet metal bar of less length than the body part of bracket 80 and formed at its ends with integral pendent pivot ears 96 and 97 which extend beyond the rear edge of said body part and are provided adjacent 45 their rear ends with conoidal bearing apertures 98. A pair of horizontally disposed bearing screws 99 are screwed inward through threaded apertures 100 in the rear ends of the bracket arms 81 and 82 and have 50 conoidal bearing portions 99^a engaged in apertures 98 in the dog rocker pivot ears, so that the dog rocker may be adjusted transversely of the machine and held in adjusted 55 position by means of the bearing screws 99 to vary the relation between the rigid or holding dog 101 and the escapement wheel 89. Lock nuts are preferably provided for holding the screws 99 in adjusted position, as shown.

60 Dog 101 is formed integrally with the main body part of the dog rocker 95 and projects forward flatwise from the forward edge of said body part with its straight wheel-tooth holding or right-hand edge 101^a extending fore-and-aft of the machine substantially on

a line through the axial line of the escapement wheel, and said dog is permanently bendable up and down for purposes of adjustment, being shown offset upwardly 70 slightly relatively to the rocker in the drawings. The pivoted or feeding dog 102 is formed of sheet metal and is pivotally held intermediate its forward and rear ends to the dog rocker by a pivot screw 103 passed upward through a bearing aperture in the 75 dog and screwed into a threaded hole 104 in the dog rocker adjacent the rear end of the holding dog.

The feeding dog 102 is formed with two integral arms 105 and 106 extending toward opposite sides of the machine from the pivot portion of the dog substantially at right angles to the dog. The nose portion of the dog 80 102 projects forward of the rocker and is formed with a straight right-hand or wheel-tooth-holding edge 102^a and a beveled or cam left-hand edge 102^b. The rearwardly extending tail portion 102^c of the dog in rear of the dog pivot, together with arms 105 and 106, wipe over the bottom face of the dog 85 rocker and afford a broad anti-tilting bearing for the dog without an undesirable amount of friction.

A pair of control devices 107 and 108 for the feeding dog co-operate with the dog arms 95 105 and 106. Each of these devices consists of a three-armed sheet metal lever, and said devices 107 and 108 are held to the main body 100 part of the dog rocker by pivot screws 109 and 110 located at opposite sides of the dog pivot and slightly in rear of a plane extending transversely of the machine through said dog pivot. The pivot screw of each device passes upward through a bearing aperture 105 in the device at the junction of the three arms, said screws 109 and 110 being screwed at 110 their upper ends into threaded holes 111 and 112 in the dog rocker and holding said devices to the under face of the dog rocker to swing in a plane parallel with the plane of the flat body part of said rocker.

The rearwardly extending arms 107^a and 108^a of said devices are formed with pendent lugs at their rear ends to which are connected the opposite ends of a helical tension 115 spring 113 of such length that said spring is under constant tension in the various positions of the controlling devices. The spring 113 normally tends to hold the outwardly extending arms 107^b and 108^b of the controlling 120 devices rocked rearward against stops 114 and 115 on the dog rocker, said stops comprising arcuate metal strips punched down from the flat body part of the dog rocker and integral therewith at their inner and outer ends, the stops being located adjacent opposite ends of the dog rocker. When the loose dog is free from the escapement wheel 89, spring 113 normally holds the forward edges 125 of the inwardly extending arms 107^c and 130

108^a of the controller flat against the rear edges of the dog arms 105 and 106, respectively, and the arms 107^b and 108^b in engagement with stops 114 and 115, to yieldably 5 maintain the feeding dog in an intermediate position (shown in Fig. 11) from which it may be rocked in either direction by a tooth of said wheel.

The feeding dog is adapted to be rocked 10 toward the left from its normal intermediate position by the teeth of the escapement wheel on return movements of the dog rocker, after engagement of the holding or straight radial edge 89^a of one of said wheel teeth 15 with the holding edge 102^a of the dog, against the resistance of spring 113 applied to the dog through controller 108 which will rock in counterclockwise direction away from stop 115 until the arm 105 of the dog engages 20 behind a stop 116 on the dog rocker, while controller 107 will be held stationary against stop 114. Stop 116 comprises a transversely extending finger formed integrally with the dog rocker body at the front edge thereof 25 and having its free end offset downward into the path of dog arm 105. Stop finger 116 is permanently bendable fore-and-aft of the machine to adjust the carriage-arresting position of the feeding dog and regulate the 30 amount of "drop" that occurs between the release of the feeding dog from, and engagement of the holding dog with, a wheel tooth on the printing stroke of a type bar.

The feeding dog is adapted to be rocked 35 toward the right from its normal intermediate position by the teeth of the escapement wheel upon reverse rotation of the wheel, as shown in Fig. 13, such reverse rotation occurring during carriage-returning 40 and back-spacing operations, and the beveled edges 89^b of the wheel teeth cooperating with the beveled edge 102^b of the dog to cam the dog intermittently toward the right to permit the wheel teeth to freely pass the dog. 45 Upon such reverse movement of the wheel, controller 108 will be held against stop 115 and controller 107 will vibrate from and to its stop 114 as each tooth of the wheel passes the dog.

50 The platen carriage 27 is normally urged from right to left by a spring drum 117 located under the carriage bed and rotatably held thereto at 118, a draw band or cable 119, wound on and attached to the drum at one 55 end, passing over a pulley 120 journalled in a slot 121 in the carriage bed and being attached at its other end to a screw 122 held to the right hand end portion of the carriage bed plate. The drum spring normally 60 tends to drive the escapement wheel in the direction indicated by the arrow in Figs. 9 and 11 through the medium of the feed rack and pinion.

A dog rocker return spring 123 is connected at its rear end with the outer end

of a lug 124 which extends outward from the lower end of dog rocker pivot ear 96, and the forward end of said spring is connected with a lug 125 depending from the forward end of bracket arm 81, said spring 70 extending upward and forward from lug 124 and being located, together with lugs 124 and 125, outside of the vibratory supporting means for the universal bar. Spring 123 normally urges the dog rocker upward and 75 rearward about its pivot, and an upwardly and forwardly extending stop arm 126 (formed integrally with dog rocker pivot ear 97 and located above the vibratory supporting means for the universal bar) normally engages at its forward end the bottom face of bracket 80 to arrest return movement of the rocker with the feeding dog 102 in the plane of the escapement wheel, said dog normally holding the carriage against 80 the pull of the spring drum and cable by reason of the engagement of its holding edge 102^a with the straight radial edge 89^a of one of the teeth of the escapement wheel 89, as most clearly shown in Figs. 5 and 9. 85

An integral arm 127 extends downward and forward from the dog rocker pivot ear 97, at the outer side of the inwardly offset rear portion of the section 50^a of the left hand side arm of the universal bar forward 90 of shaft 36, and is provided at its lower end with an outwardly extending contact lug 128 normally lying flatwise in a plane perpendicular to wall 13 and the path of movement of the shift frame and extending behind the lower portions of the rear contact edges of tappets 166 and 178. As the contact edge of each tappet is parallel with the path of shift of the shift frame and is made long enough to engage the narrow forward edge 95 of contact lug 128 in both case positions of the shift frame, it will be obvious that each tappet will rock the dog rocker uniformly 100 in both case positions of the shift frame. 105

As shown, tappet 166 is located slightly 110 forward of tappet 178 which normally engages, or substantially engages, with the contact lug. By this arrangement the escapement may be tripped by a short dip of the space bar 167, and universal bar 49 will move the ribbon actuator throughout its rearward travel and will trip the dog rocker during the last part of its rearward travel, thereby rendering proper action of the ribbon mechanism (and particularly the ribbon vibrating means) more certain, and providing for 115 speedy action of the escapement during a small final part of the printing stroke and a corresponding initial part of the return stroke of a type bar, and also contributing to 120 easy operation of the keys by providing for successively starting operation of the type bar, the ribbon mechanism, and the escapement mechanism during the down stroke of 125 a character key. 130

As hereinbefore described, means are provided for preventing overthrow of the universal bar and its connected tappet 166 and of the space bar and its connected tappet 5 178. Means have also been provided for preventing overthrow of the dog rocker upon violent or rapid rearward movement of either of said tappets. This latter means comprises a bell-crank lever having an arm 129 extending downwardly and rearwardly under bracket 80 between bracket arm 82 and stop arm 126 and provided at its rear end with a lateral extension 129^a extending inward over stop arm 126 forward of the body part of the dog rocker and then under an integral stop lug 130 projecting forward from the body of the dog rocker at the left of the holding dog 101. A horizontally and transversely extending shouldered pivot 10 screw 131 extends inward through and is journalled in a bearing hole 132 formed in the forward end of bracket arm 82, and the reduced threaded inner end of said screw is threaded in a screw-threaded hole 133 in the forward end of the lever arm 129. The second arm 134 of the bell-crank lever extends upward and rearward from the forward end of arm 129 through a fore-and-aft extending slot 135 in the carriage bed 28 into the space between the carriage bed and the base plate of the carriage. A spring 136 extends downward and rearward from a lug 137 formed on the bell-crank lever forward of the pivot of the lever to a lug 138 15 formed on bracket arm 82. Spring 136 normally holds bell-crank lever 129—134 in the position shown in Figs. 1, 5, 7, 9, 10, 15 and 17 in which an upstanding stop lug 139 on lever arm 129 (in rear of the lever pivot) engages the bottom face of bracket 80 alongside the forward end of stop arm 126, with the lower edge of extension 129^a of lever arm 129 spaced above stop arm 126, and with the upper edge of said extension 129^a spaced 20 below stop lug 130 on the dog rocker. Extension 129^a forms a spring-held stop arranged to be engaged by lug 130 to quietly arrest the forward and downward tripping movement of the dog rocker when the holding dog 101 has moved down into the plane of the escapement wheel 89, as shown in Figs. 7, 11, and 12, engagement of lug 130 with extension 129^a taking place when the dog 101 is in position to catch and hold the wheel tooth from which dog 102 has just been released and while stop 139 on lever arm 129 still remains engaged with bracket 80. Stop lug 130 is bendable up and down for purposes of adjustment. 25 Provision has been made for releasing the carriage by hand for running movement in either direction. The carriage releasing means comprises the bell-crank 129—134 and a sheet metal bail 140, the cross-bar of which 30 extends between the base plate of the carriage and the carriage bed in front of arm 134 of the bell-crank. The side arms of the bail 140 extend upward at the ends of the carriage behind the platen shaft 18^a and are pivoted on horizontal pivot screws 141 35 threaded into the end plates of the carriage intermediate the ends of said side arms. The side arms are formed with finger pieces 140^a at their upper ends projecting above the platen shaft. The bail is normally held in the position shown in Figs. 1, 5, and 7 by the spring-returned bell-crank 129—134. Upon forward rocking of the finger pieces 140^a by the operator until arrested by stop studs 142 (held to and projecting outward from the carriage end plates), the bail and bell-crank 129—134 move to the position shown in Fig. 8, wherein the stop arm 126 on the dog rocker has been engaged by bell-crank extension 129^a and depressed sufficiently to 40 rock the dog rocker forward and downward from normal position and far enough past the position shown in Figs. 7, 11 and 12 to carry both escapement dogs down below the plane of the wheel, which is thus completely freed from the dogs so that the carriage may be freely run toward the left, and whereby the carriage may be also run toward the right (if desired) without the ratching action of dog 102 shown in Fig. 13 45 and hereinbefore described. Upon release of the finger pieces, the bail, bell-crank and dog rocker will be returned to normal position by the springs 123 and 136, and dog 102 will engage one of the teeth of wheel 89 and hold the carriage in its adjusted position. 50 Simple means has been provided co-operative with the forward feeding means above described to effect step-by-step backward feeding of the carriage, in either case 55 position of the shift frame, from a back-space key located in the keyboard of the machine. The back-spacing dog 143 is formed on, and extends rearwardly from, the left hand end of a sheet metal dog-carrying bar 144 at the right of the feed pinion. The dog carrier 144 lies flatwise between the carriage base plate and the carriage bed and extends toward the right from dog 143 to a point 60 in front of an opening 145 formed in the carriage bed adjacent the right hand end of the bed. A screw 146 extends down through a longitudinal slot 147 in the middle portion of the dog carrier and is threaded into the carriage bed 28 to slidably and rockably hold the dog carrier on the upper face of the carriage bed. A dog carrier return spring 148, connected at its inner end with an integral lug 149 formed on the right hand end of bracket 65 60, and connected at its right hand end with an integral lug 150 extending rearward from carrier 144 at a point to the right of slot 147 and then downward through a longitudinal slot 151 in the carriage bed to the rear of the forward edge of said slot 151, normally 70

holds the dog carrier in the position shown in Fig. 6, wherein the screw is engaged against the outer end of slot 147 and dog 143 is rocked forward out of feed rack 93. The spring 148 extends slightly rearward from lug 149 to lug 150 and normally slides the carrier inward, and rocks its dog carrying end forward and its outer end rearward against an up-standing lug 152 formed on the rear end of 10 the rearwardly extending arm of a bell-crank lever 153. Lever 153 is pivotally held to the under face of the carriage bed (by a pivot screw 154 threaded upward into said bed) to rock in a plane parallel with the plane 15 of the bed, and lug 152 extends up through the opening 145 in the bed at the left hand end of a lug 155 projecting rearward from the outer end of the dog carrier. Lug 155 is formed at its left side with a rearwardly 20 and outwardly extending cam edge 155^a terminating in a fore-and-aft extending shoulder 155^b, and the lug has a fore-and-aft extending stop edge 155^c at its right side normally spaced toward the left from an up-standing stop lug 156 formed on one of the 25 ribbon mechanism supporting brackets 157 of the machine. Bracket 157 is fastened to the under face of the carriage bed by screws, of which screw 154 is one, and lug 156 projects up through opening 145 into the path 30 of movement of edge 155^c of lug 155 on the dog carrier 144.

Lever 153 has its second arm extending outward from its pivot and connected with the 35 rear end of a link 158 which in turn is connected at its forward end with the upwardly and rearwardly extending arm of a bell-crank back-space key lever 159. The key-carrying arm of the back-space key lever extends 40 forward from the pivot of the lever through one of the guide slots of the comb 22 and supports the back-space key at the right hand side of the keyboard. This key lever is fulcrumed on a horizontal pivot screw 160 passing outward through the lever at the junction 45 of its two arms and threaded into the right hand bracket 39. The rear arm of the lever is formed with a rearwardly extending lug 161 from which a return spring 162 extends 50 downward and forward and is anchored to the anchor bar 75. Spring 162 normally holds the forward arm of the key lever up against the key-lever-stop cushion 163 held to comb 22 to thereby determine the normal 55 positions of the several parts of the back-spacing mechanism.

Link 158 extends rearward and downward 60 from the key lever and is adapted to swing about its connection with the key lever upon an upper case movement of the shift frame, the rear end of the link moving from a point below a plane through said point of connection and perpendicular to the path of case shift movement of the frame to a point substantially the same distance above said plane,

so that the back space key will impart the same movement to the back-space-dog carrier in both case positions of the shift frame.

Upon depression of the back space key, lug 152 on the bell-crank 153 swings outwardly 70 over cam edge 155^a of lug 155 on the dog carrier to rock the dog 143 into engagement with the left hand edge of a tooth of rack 93 and then pushes outward against the lug shoulder 155^b to slide the dog carrier 144 endwise to- 75 ward the right to draw the carriage backward or to the right until the tooth next in advance of the held tooth of escapement wheel 89 has cammed past the oppositely tiltable feeding dog 102 in the manner shown in Fig. 13. As 80 soon as the tooth in advance of the previous- 85 ly held tooth clears dog 102, said dog snaps into its normal intermediate position and stop edge 155^c of lug 155 abuts stop lug 156 on bracket 157 and prevents further movement of the back-spacing means. Upon release of the back space key, the back space key lever and dog return to normal position and escapement wheel tooth which has been cammed back past dog 102 advances and engages edge 90 102^a of the dog, as the carriage moves slightly toward the left again under the pull of the spring drum, and rocks said dog in the opposite direction to carriage-arresting position with its arm 105 engaged with stop 116, and 95 the carriage is then held in a position one letter-space farther toward the right than that occupied before depression of the back space key.

It will be observed that an efficient escapement mechanism has been provided wherein 100 the feeding dog is adapted to rock in opposite directions from a normal intermediate position and is controlled by means insuring quick, positive and quiet action of the dog; 105 that a compact assembly of rotary escapement and type-bar-operated universal bar mechanism and space bar mechanism for actuating the same is provided wherein the escapement mechanism is located above and 110 outside of the universal bar mechanism and space bar mechanism; that a simple escapement releasing means is provided; that means are provided for preventing overthrow of 115 the dog rocker upon actuation of a character key or the space bar; that simple feed means has been provided for advancing and retracting the carriage; and that the entire escapement mechanism except the feed rack and spring drum and cable is assembled on a 120 single bracket and may be readily attached and removed with the bracket as a unit.

As hereinbefore described, the provision 125 of tail piece 102^c on the pivoted feeding dog gives the dog an antitilting wiping engagement with the bottom face of the dog rocker 95 at both sides of its bearing on the shoul- 130 dered pivot screw 103. The reduced threaded portion of the screw, which is threaded through the screw hole 104 in the dog rocker

- preferably has a lock nut 103^a screwed thereon tightly against the top face of the dog rocker to clamp the shoulder of the screw against the bottom face of the rocker. In the 5 event of the dog being somewhat thinner than the length of the pivot portion of the shank of the shouldered screw, tail piece 102^c is bent upward until said tail piece and the dog 102 both wipe on the under face of the dog rocker 10 at all times, thus preventing wabbling of the dog on its pivot, and maintaining the nose of the pivoted feeding dog in the proper plane with respect to the fixed dog 101 at all times. In order to prevent possible overthrow of 15 the carriage in back-spacing, due to momentum acquired by the carriage upon a rapid or violent depression of the back space key, a rearwardly facing shoulder 155^a is provided on the back space dog carrier 144, which 20 shoulder engages behind stop lug 156 at the end of the down stroke of said key as stop edge 155^c engages said stop lug 156. It will be seen that this arrangement will prevent that tooth of rack 93 which follows the 25 tooth engaged by the back space dog 143 from camming the dog out of the rack at the end of the movement of the dog carrier by the back space key when the carriage is jerked violently toward the right.
- 30 What we claim is:
1. In a typewriting machine, the combination of a power-driven platen carriage, a toothed escapement wheel, a holding dog, a pivoted feeding dog shiftably in opposite directions about its pivot from a normal intermediate position by the teeth of said wheel, a pair of pivoted controllers for said dog engageable therewith at opposite sides of the pivot of the dog, and a single tension spring 35 connecting said controllers and normally urging the controllers in opposite directions about their pivots against the dog to yieldably hold the dog in its normal intermediate position.
  2. In a typewriting machine, the combination of a power-driven platen carriage, a toothed escapement wheel, a holding dog, a pivoted feeding dog shiftably in opposite directions about its pivot from a normal intermediate position by the teeth of said wheel, a pair of pivoted controllers for said dog engageable therewith at opposite sides of the pivot of the dog, a single tension spring 40 connecting said controllers and normally urging the controllers in opposite directions about their pivots against the dog to yieldably hold the dog in its normal intermediate position.
  3. In a typewriting machine, the combination of a power-driven carriage, a toothed escapement wheel geared to said car-
- riage, a dog rocker pivoted to rock about an axis perpendicular to the axis of rotation of said wheel, a feeding dog shiftably mounted on said dog rocker for movement in opposite directions by the teeth of said wheel, a pair of controllers for said feeding dog shiftably mounted on said dog rocker, a single tension spring connecting said controllers and urging the same in opposite directions, said controllers being arranged to exert opposing thrusts on the feeding dog under the pull of said spring to normally yieldably hold the feeding dog in an intermediate position, and a holding dog rigidly mounted on the dog rocker.
4. In a typewriting machine, the combination of a power driven carriage, a toothed rotary escapement wheel geared to said carriage, a dog rocker pivoted to rock about an axis perpendicular to the axis of rotation of said wheel, a feeding dog shiftably mounted on said dog rocker for movement in opposite directions by the teeth of said wheel, a pair of controllers for said feeding dog shiftably mounted on said dog rocker, a single tension spring connecting said controllers and urging the same in opposite directions, said controllers being arranged to exert opposing thrusts on the feeding dog under the pull of said spring to normally yieldably hold the feeding dog in an intermediate position, a holding dog rigidly mounted on the dog rocker, means for normally yieldably holding the dog rocker in a position in which the feeding dog is engaged with a tooth of the wheel, and character key-operated means for rocking the dog rocker about its pivot to release the feeding dog and bring the holding dog into engagement with a wheel tooth to hold the wheel during movement of the feeding dog 105 to its normal intermediate position.
5. In a typewriting machine, an escapement mechanism comprising an escapement wheel, a holding dog, a feeding dog capable of occupying three different positions, and a pair of pivoted controllers connected by a single tension spring and arranged to coact with the feeding dog to normally maintain said dog in its intermediate position.
6. In a typewriting machine, an escapement mechanism comprising an escapement wheel, a holding dog, a feeding dog capable of occupying three different positions, a pair of pivoted controllers connected by a single tension spring and arranged to coact with the feeding dog to normally maintain said dog in its intermediate position, means for limiting pivotal movements of said controllers under the pull of said spring, and means for positively arresting the feeding dog in one of its end positions.
7. In an escapement mechanism, a toothed escapement wheel, a vibratable dog carrier, a holding dog on said carrier, a feeding dog mounted on said carrier for movement by 130

teeth of said wheel to either side of a central normal position, a pair of controllers pivoted on said carrier to abut and exert opposing thrusts on said feeding dog, and a tension spring connected at its opposite ends with said controllers to swing the same in opposite directions about their pivots into contact with said dog to normally hold the dog yieldably in its central position.

8. In an escapement mechanism, a toothed escapement wheel, a vibratable dog carrier, a holding dog on said carrier, a feeding dog pivotally held to said carrier for rocking thereof by teeth of said wheel in opposite directions from a normal central position, a stop on the carrier engageable by the feeding dog for arresting swinging of the dog in one direction while still engaged by a tooth of said wheel, a pair of pivoted controllers mounted on said carrier engageable with the feeding dog at opposite sides of its pivot, a tension spring connected at its ends with said controllers to rock the same in opposite directions about their pivots into engagement with the feeding dog, and means on the carrier for holding each controller stationary upon movement of the other controller against the pull of said spring by the dog upon swinging of the dog out of its central position by an escapement wheel tooth, said means being arranged to permit engagement of both controllers with the dog while the dog is in central position.

9. In an escapement mechanism, a rotary toothed escapement wheel, means normally urging said wheel to rotate in one direction, a vibratable dog carrier, a holding dog on said carrier, a feeding dog pivoted on said carrier for movement to opposite sides of a central normal position by teeth of said wheel, said feeding dog having a pair of arms extending in opposite directions from its pivot, a pair of levers pivoted on said dog carrier on axes parallel with the pivotal axis of the feeding dog and located at opposite sides of the feeding dog pivot, said levers having inwardly extending arms cooperative with the outwardly extending arms of the feeding dog to rock the dog in opposite directions and arms at an angle to said inwardly extending arms, a tension spring connecting the latter arms of the levers to rock the respective levers in a direction to cause the inwardly extending lever arms to normally contact with the feeding dog arms and yieldably hold the feeding dog in central position, and stop means on the carrier cooperating with the levers to hold one lever stationary against the pull of said spring when the other lever is rocked against the pull of the spring by a swinging movement of the dog from its central position.

10. In an escapement mechanism, a rotary toothed escapement wheel, means normally urging said wheel to rotate in one direction, a vibratable dog carrier, a holding dog on said

carrier, a feeding dog pivoted on said carrier for movement to opposite sides of a central normal position by teeth of said wheel, said feeding dog having a pair of arms extending in opposite directions from its pivot, a pair of levers pivoted on said dog carrier on axes parallel with the pivotal axis of the feeding dog and located at opposite sides of the feeding dog pivot; said levers having inwardly extending arms and arms disposed at an angle to the inwardly extending arms, a tension spring connecting the last-mentioned lever arms to rock the levers in opposite directions, and a pair of stops on the carrier engageable by the levers to arrest pivotal movement of the levers under the pull of said spring, said stops being arranged to permit the arms of the feeding dog to engage said inwardly extending lever arms when the dog is in central position, and said inwardly extending lever arms engaging corresponding edges of the dog arms so as to offer opposing resistance to movement of the dog from central position.

11. In an escapement mechanism, a vibratory dog carrier, a rigid holding dog on said carrier, a pivoted feeding dog on said carrier, a toothed member normally urged in one direction and movable in the opposite direction, means for vibrating the carrier to position the dogs for engagement alternately with teeth of said member, a pair of pivoted devices engageable by the pivoted dog to normally yieldably hold the dog in an intermediate position from which it is movable in opposite directions against the resistance of different ones of said devices by teeth of said member in accordance with the direction of movement of the member, stopping means for determining the normal position of said devices, and spring means urging said devices about their pivots to normal position.

12. In an escapement mechanism, a vibratory dog carrier, a rigid holding dog on said carrier, a pivoted feeding dog on said carrier, a toothed member normally urged in one direction and movable in the opposite direction, means for vibrating the carrier to position the dogs for engagement alternately with teeth of said member, a pair of pivoted devices engageable by the pivoted dog to normally yieldably hold the dog in an intermediate position from which it is movable in opposite directions against the resistance of different ones of said devices by teeth of said member in accordance with the direction of movement of the member, stopping means on the carrier for arresting pivotal movement of each of said devices in one direction to determine the normal position of the device, spring means urging said devices constantly toward normal position, and stopping means on the dog carrier for arresting pivotal movement of the feeding dog from its normal intermediate position by a tooth of the toothed member during movement of said member in normal

direction while said dog is still engaged by said tooth.

13. In an escapement mechanism, a vibratory dog carrier, a rigid holding dog on said carriage, a pivoted feeding dog on said carrier, a toothed member normally urged in one direction and movable in the opposite direction, means for vibrating the carrier to position the dogs for engagement alternately with teeth of said member, a pair of pivoted devices engageable by the pivoted dog to normally yieldably hold the dog in an intermediate position from which it is movable in opposite directions against the resistance of different ones of said devices by teeth of said member in accordance with the direction of movement of the member, stopping means on the carrier for arresting pivotal movement of each of said devices in one direction to determine the normal position of the device, spring means urging said devices constantly toward normal position, stopping means on the dog carrier for arresting pivotal movement of the feeding dog from its normal intermediate position by a tooth of the toothed member during movement of said member in normal direction while said dog is still engaged by said tooth, and key-operated back-spacing means for driving said toothed member in reverse direction.

14. In a typewriting machine, a reciprocable platen carriage spring-driven in one direction, a toothed member movable in opposite directions by reciprocatory movements of the carriage, a vibratory dog carrier, a holding dog rigidly mounted on the carrier, a feeding dog pivotally mounted on the carrier for swinging movement to opposite sides of a normal central position by teeth of said member, means connected with the carrier for normally holding the carrier in position for engagement of the feeding dog with a tooth of said member, character-key-operated means for shifting said carrier to position the holding dog for engagement with a tooth of said member and freeing the feeding dog, a pair of devices pivotally mounted on the carrier for engagement thereof by the feeding dog, stopping means on the carrier for determining the normal position of said devices, said devices when in normal position being engaged with the dog to resist movement of the dog in both directions from its normal central position, spring means constantly urging said devices about their pivots toward said stopping means, and means for positively arresting pivotal movement of the feed dog from central position by a tooth of said member while said dog and tooth are still engaged upon an advancing movement of the carriage by its driving spring.

15. In a typewriting machine, a reciprocable platen carriage spring-driven in one direction, a toothed member movable in opposite directions by reciprocatory movements

of the carriage, a vibratory dog carrier, a holding dog rigidly mounted on the carrier, a feeding dog pivotally mounted on the carrier for swinging movement to opposite sides of a normal central position by teeth of said member, means connected with the carrier for normally holding the carrier in position for engagement of the feeding dog with a tooth of said member, character-key-operated means for shifting said carrier to position the holding dog for engagement with a tooth of said member and freeing the feeding dog, a pair of devices pivotally mounted on the carrier for engagement thereof by the feeding dog, stopping means on the carrier for determining the normal position of said devices, said devices when in normal position being engaged with the dog to resist movement of the dog in both directions from its normal central position, spring means constantly urging said devices about their pivots toward said stopping means, means for positively arresting pivotal movement of the feed dog from central position by a tooth of said member while said dog and tooth are still engaged upon an advancing movement of the carriage by its driving spring, and key-operated back-spacing means for shifting the carriage in opposition to its driving spring a distance sufficient to force the tooth of said member next in advance of the tooth engaged by the feeding dog back past the said oppositely movable feeding dog at each operation of said back-spacing means.

16. In a typewriting machine, a carriage support, a reciprocable platen carriage spring-driven in one direction and mounted on said support, a feed rack held to the carriage, a feed pinion meshing with said rack, a toothed escapement wheel held to rotate with said pinion, a pivoted dog carrier, a holding dog on said carrier, a feeding dog pivoted on said carrier to swing in opposite directions from a central normal position, a pair of controllers pivotally mounted on the dog carrier and loosely engageable by the feeding dog at different sides of its pivot, a tension spring connecting said controllers to adapt the same to arrest the feeding dog in central position, stops on the carrier engageable by the controllers to limit pivotal movement of the controllers under the pull of said spring, a stop on the carrier for arresting pivotal movement of the feeding dog from central position by a tooth of the escapement wheel upon rotation of said wheel under the influence of the carriage driving spring while said dog and tooth are still engaged, a spring connected with the dog carrier for normally holding the carrier in position for engagement of the feeding dog with a tooth of the escapement wheel, and character key-operated means for rocking the carrier to a position in which the feeding dog is released

from and the holding dog engaged by a tooth of said wheel.

17. In a typewriting machine, a carriage support, a reciprocable platen carriage spring-driven in one direction and mounted on said support, a feed rack held to the carriage, a feed pinion meshing with said rack, a toothed escapement wheel held to rotate with said pinion, a pivoted dog carrier, a holding dog on said carrier, a feeding dog pivoted on said carrier to swing in opposite directions from a central normal position, a pair of controllers pivotally mounted on the dog carrier and loosely engageable by the feeding dog at different sides of its pivot, a tension spring connecting said controllers to adapt the same to arrest the feeding dog in central position, stops on the carrier engageable by the controllers to limit pivotal movement of the controllers under the pull of said spring, a stop on the carrier for arresting pivotal movement of the feeding dog from central position by a tooth of the escapement wheel upon rotation of said wheel under the influence of the carriage driving spring while said dog and tooth are still engaged, a spring connected with the dog carrier for normally holding the carrier in position for engagement of the feeding dog with a tooth of the escapement wheel, character key-operated means for rocking the carrier to a position in which the feeding dog is released from and the holding dog engaged by a tooth of said wheel, and a back-space-key-operated back-spacing dog shiftably mounted on the carriage support normally disengaged from said feed rack and operable upon depression of the back-space key to engage and move the rack in opposition to the carriage driving spring a distance sufficient to force one tooth of the escapement wheel back past the feeding dog.

18. In a typewriting machine, a traveling platen carriage, a toothed escapement member connected with the carriage, a pivotally supported dog rocker, a pair of escapement dogs on said rocker engageable alternately with said member, stopping means for determining the normal position of the rocker, a spring connected with the rocker and urging it to normal position, key-operated means loosely engageable with the rocker for moving the rocker from normal position, an overthrow-preventing stop for said key-operated means, and a spring-held overthrow-preventing stop engageable by the dog rocker to arrest the same with the normally disengaged dog in position for engagement with the toothed escapement member.

19. In a typewriting machine, a traveling platen carriage, a toothed escapement member connected with the carriage, a pivotally supported dog rocker, a pair of escapement dogs on said rocker engageable alternately with said member, stopping means for determining the normal position of the rocker, a

spring connected with the rocker and urging it to normal position, key-operated means loosely engageable with the rocker for moving the rocker from normal position, an overthrow-preventing stop for said key-operated means, a spring-held overthrow-preventing stop engageable by the dog rocker to arrest the same with the normally disengaged dog in position for engagement with the toothed escapement member, said spring held stop being operative on the dog rocker upon movement of said stop in opposition to its spring to swing the dog rocker to a position in which the toothed escapement member is free from the control of the dogs, and means for at will moving said stop in opposition to its spring.

20. In a typewriting machine, a platen carriage, an escapement for the carriage including a dog rocker, an overthrow preventing device for the dog rocker, and hand-operated means for manipulating said device to cause the same to shift the dog rocker to a position in which the carriage is free from the control of the escapement.

21. In an escapement mechanism, a toothed member normally urged in one direction, a vibratory dog carrier, dogs on said carrier co-operative with said member to feed the same step by step, means for vibrating the carrier, a device co-operative with the carrier to normally prevent overthrow of the carrier, and hand-operated means for manipulating said device to impart an excessive movement to the carrier at will to release the toothed member from the control of the dogs.

22. In an escapement mechanism, a toothed escapement member normally urged in one direction, a vibratory dog carrier, dogs on said carrier co-operative with said toothed member to control the feed thereof, means co-operative with the carrier to limit its movement in opposite directions to prevent accidental freeing of said member from the control of the dogs, said means including a shiftable device normally held in position for engagement thereof by the dog carrier to prevent overthrow of the dog carrier in one direction, and manually operable escapement releasing means connected with said device for forcing said device against a part of the dog carrier in a direction to positively move the dog rocker beyond the point at which it is normally arrested by said device.

23. In an escapement mechanism, a pivoted dog carrier, a device pivoted to swing about an axis parallel with the pivotal axis of the dog carrier, said carrier having spaced abutments between which said device extends, a spring urging said device in one direction, means for holding said device against the tension of said spring in a position to coact with one of said abutments to arrest movement of the dog carrier in one direction to prevent overthrow of the carrier, and manually operable escapement releasing means

for swinging said device against the tension of its spring to cause the device to cooperate with the other abutment to overthrow the dog rocker and thereby release the escapement.

- 5 24. In a typewriting machine escapement, a toothed escapement member spring urged in one direction, a dog rocker support, a dog rocker pivoted on said support, holding and feeding dogs on said rocker alternately engageable with said toothed member, a spring urging the rocker in one direction, a stop arm on said rocker normally engaging said rocker support to prevent overthrow of the rocker by its spring, said feeding dog normally engaging a tooth of said member, key-operated tappet means for rocking the rocker against the tension of its spring, a device pivoted on said rocker support to swing about an axis parallel with the pivotal axis of the rocker 20 and extending between said arm and a rigid part of the rocker, a spring connected with said device normally urging the same away from said arm against the rocker support, said device being normally held spaced from 25 said rigid part of the rocker by the rocker support in position to arrest movement of the rocker by said tappet means when the holding dog reaches a position for engagement with the toothed member, and hand-operated 30 release means connected with said device to swing the device in opposition to its connected spring to rock the dog rocker through the medium of said stop arm a distance sufficient to carry both dogs out of cooperative relation with the toothed member.
25. In a typewriting machine, a platen carriage having a base plate, a metal member comprising two webs disposed substantially at a right angle to each other, screws detachably holding one web of said member against one edge of the carriage base plate with the other web of said member extending under the base plate, and a carriage bearing roller rotatably held to said screw-held web, the 40 web extending under the base plate being toothed along its edge to form a feed rack for the carriage escapement.
- 45 26. In a typewriting machine, a platen carriage having a base plate, a metal member comprising two webs disposed substantially at a right angle to each other, screws detachably holding one web of said member against one edge of the carriage base plate with the other web of said member extending under the base plate, a carriage bearing roller rotatably held to said screw-held web, the web 55 extending under the base plate being toothed along its edge to form a feed rack for the carriage escapement, and a rotary escapement device geared to said rack.
- 60 27. In a typewriting machine, a platen carriage having a base plate, a metal member comprising two webs disposed substantially at a right angle to each other, screws detachable holding one web of said member against one edge of the carriage base plate with the other web of said member extending under the base plate, a carriage bearing roller rotatably held to said screw-held web, the web 65 extending under the base plate being toothed along its edge to form a feed rack for the carriage escapement, a support for the carriage having a track thereon for said roller, a bracket detachably held to said support, a shaft journaled on said bracket, a feed pinion on said shaft meshing with said feed rack, an escapement wheel on said shaft, a dog rocker mounted on said bracket, and dogs on said rocker cooperative with said wheel.
- 70 28. In an escapement, an assembly comprising a sheet metal bracket having a flat body part formed with depending end portions and having an opening in said body part, a bushing extending through and swaged in said opening, a shaft extending through said bushing and having an integral feed pinion formed on its upper end, said shaft having a collar thereon seated on the upper end of said bushing and a reduced non-circular lower end portion projecting below the lower end of the bushing, a sheet metal escapement wheel abutting the lower end of the bushing and having a central opening in which said reduced end portion of the shaft is engaged, said wheel opening conforming to the contour of said reduced end portion of the shaft, said shaft having a threaded axial bore at its lower end, a washer abutting the end of the shaft and the under face of said wheel, and a retaining screw having a shank passing upwardly through said washer and screwed into said bore.
- 75 29. In an escapement, an assembly comprising a sheet metal bracket having a flat body part formed with depending end portions and having an opening in said body part, a bushing extending through and swaged in said opening, a shaft extending through said bushing and having an integral feed pinion formed on its upper end, said shaft having a collar thereon seated on the upper end of said bushing and a reduced non-circular lower end portion projecting below the lower end of the bushing, a sheet metal escapement wheel abutting the lower end of the bushing and having a central opening in which said reduced end portion of the shaft is engaged, said wheel opening conforming to the contour of said reduced end portion of the shaft, said shaft having a threaded axial bore at its lower end, a washer abutting the end of the shaft and the under face of said wheel, a retaining screw having a shank passing upwardly through said washer and screwed into said bore, a sheet metal dog rocker pivotally supported on the depending end portions of the bracket, holding and feeding dogs on said rocker cooperative with said wheel, and a return spring for the dog rocker connecting the dog rocker with the bracket.

80 one edge of the carriage base plate with the other web of said member extending under the base plate, a carriage bearing roller rotatably held to said screw-held web, the web extending under the base plate being toothed along its edge to form a feed rack for the carriage escapement, a support for the carriage having a track thereon for said roller, a bracket detachably held to said support, a shaft journaled on said bracket, a feed pinion on said shaft meshing with said feed rack, an escapement wheel on said shaft, a dog rocker mounted on said bracket, and dogs on said rocker cooperative with said wheel.

85 28. In an escapement, an assembly comprising a sheet metal bracket having a flat body part formed with depending end portions and having an opening in said body part, a bushing extending through and swaged in said opening, a shaft extending through said bushing and having an integral feed pinion formed on its upper end, said shaft having a collar thereon seated on the upper end of said bushing and a reduced non-circular lower end portion projecting below the lower end of the bushing, a sheet metal escapement wheel abutting the lower end of the bushing and having a central opening in which said reduced end portion of the shaft is engaged, said wheel opening conforming to the contour of said reduced end portion of the shaft, said shaft having a threaded axial bore at its lower end, a washer abutting the end of the shaft and the under face of said wheel, and a retaining screw having a shank passing upwardly through said washer and screwed into said bore.

90 29. In an escapement, an assembly comprising a sheet metal bracket having a flat body part formed with depending end portions and having an opening in said body part, a bushing extending through and swaged in said opening, a shaft extending through said bushing and having an integral feed pinion formed on its upper end, said shaft having a collar thereon seated on the upper end of said bushing and a reduced non-circular lower end portion projecting below the lower end of the bushing, a sheet metal escapement wheel abutting the lower end of the bushing and having a central opening in which said reduced end portion of the shaft is engaged, said wheel opening conforming to the contour of said reduced end portion of the shaft, said shaft having a threaded axial bore at its lower end, a washer abutting the end of the shaft and the under face of said wheel, a retaining screw having a shank passing upwardly through said washer and screwed into said bore, a sheet metal dog rocker pivotally supported on the depending end portions of the bracket, holding and feeding dogs on said rocker cooperative with said wheel, and a return spring for the dog rocker connecting the dog rocker with the bracket.

30. In a typewriting machine, a carriage bed, a platen carriage, a feed rack held to the carriage, an escapement releasing bail pivoted on the carriage, a bracket detachably held to the bed, a dog rocker mounted on the bracket, a shaft journalled on the bracket, a feed pinion on said shaft meshing with said rack, an escapement wheel on said shaft, escapement dogs on the rocker cooperative with said wheel, a device pivoted on the bracket and loosely engaged by said bail and operable by the bail to rock the dog rocker for releasing the escapement, and a stop on the dog rocker engageable with said device to prevent overthrow of the dog rocker in one direction.

31. In a typewriting machine, a carriage bed, a carriage mounted on the bed to travel thereover, a feed rack held to the carriage and located between the carriage and bed, a bracket detachably held to the under face of the bed, a shaft journalled on said bracket and extending through the bed, a feed pinion on said shaft between the carriage and bed meshing with said rack, said bed having an opening through which said pinion may pass, an escapement wheel on the lower end of said shaft, a dog rocker pivoted on said bracket, a release bail pivoted on the ends of the carriage to swing fore-and-aft and having its cross bar extending between the carriage and bed, holding and feeding dogs on the rocker cooperative with said wheel, a lever pivoted on the bracket on a pivot extending transversely of the machine and having one arm extending upward through the bed and loosely engaged by the cross-bar of the release bail and an arm below the bed arranged to impart an excessive tripping movement to the dog rocker, and a return spring for said lever and bail connecting the lever with the bracket.

32. In a typewriting machine, a carriage bed, a carriage mounted on the bed to travel thereover, a feed rack held to the carriage and located between the carriage and bed, a bracket held to the under face of the bed, a shaft journalled on said bracket and extending through the bed, a feed pinion on said shaft between the carriage and bed meshing with said rack, an escapement wheel on the lower end of said shaft, a dog rocker pivoted on said bracket, a release bail pivoted on the ends of the carriage to swing fore-and-aft and having its cross bar extending between the carriage and bed, holding and feeding dogs on the rocker cooperative with said wheel, a lever pivoted on the bracket on a pivot extending transversely of the machine and having one arm extending upward through the bed and engaged by the cross-bar of the release bail and an arm below the bed arranged to impart an excessive tripping movement to the dog rocker, a return spring for said lever and bail connecting the lever with the bracket, a back-spacing dog mounted

on the upper face of the carriage bed and cooperative with said feed rack, a universal bar and a space bar connected with the dog rocker, and a back-space key connected with the back space dog.

33. In a typewriting machine, a traveling platen carriage, a toothed escapement member connected with the carriage and spring urged in one direction, a pivoted dog carrier supported independently of the carriage, rigid and pivoted dogs on said carrier engageable alternately with said toothed member, a return spring urging the dog carrier in one direction about its pivot, a stop arm rigidly held to the dog carrier normally engaging a stationary part of the machine to arrest movement of the dog carrier by its return spring with one of said dogs in position for engagement with said toothed member, a universal bar, means operable by said universal bar for rocking the dog carrier in opposition to its return spring, a stop member pivotally supported independently of the dog carrier and carriage and engageable by the dog carrier to arrest the dog carrier with the other dog thereon in position for engagement with the toothed member, and a spring connected with said pivoted stop member to resist movement of the stop member when engaged by the dog rocker and normally holding the stop member against a fixed part of the machine to determine the normal position of said stop member.

34. In a typewriting machine, a traveling platen carriage, a toothed escapement member connected with the carriage and spring urged in one direction, a dog carrier pivotally supported independently of the carriage to rock about an axis parallel with the path of travel of the carriage, rigid and pivoted dogs on said carrier engageable alternately with said toothed member, a return spring urging the dog carrier in one direction about its pivot, a stop arm rigidly held to the dog carrier normally engaging a stationary part of the machine to arrest movement of the dog carrier by its return spring with one of said dogs in position for engagement with said toothed member, a universal bar, means operable by said universal bar for rocking the dog carrier in opposition to its return spring, a stop member pivotally supported independently of the dog carrier and carriage to rock about an axis parallel with the pivotal axis of the dog carrier and engageable by the dog carrier to arrest the dog carrier with the other dog thereon in position for engagement with the toothed member, a spring connected with said pivoted stop member to resist movement of the stop member when engaged by the dog rocker and normally holding the stop member against a fixed part of the machine to determine the normal position of said stop member, and a hand-operated escapement-releasing member pivoted on the carriage to

swing about an axis parallel with the path of travel of the carriage and having an abutting contact with the pivoted stop member in all positions of the traveling carriage, said releasing member being rockable in one direction by said pivoted stop member and its connected spring and being manually rockable in the opposite direction to swing the pivoted stop member against the resistance of its spring, said stop member when rocked by said releasing member being arranged to exert pressure on the stop arm on the dog carrier and rock said carrier against the resistance of the carrier return spring beyond the normal point of arrest of the carrier by said pivoted stop member.

35. In a typewriting machine, a traveling spring-driven platen carriage, a toothed escapement member normally driven in one direction from the carriage, a dog rocker, pivotally supported independently of the carriage, escapement dogs on said rocker, a return spring connected with the dog rocker, stopping means for arresting return movement of the dog rocker, tappet means for actuating the dog rocker against the resistance of its return spring, a stop member pivotally supported independently of the dog rocker and normally spaced therefrom and engageable by the rocker upon actuation of said tappet means, and a spring connected with the pivoted stop member and yieldably holding the same in position to prevent overthrow of the rocker when the tappet means is actuated.

36. In a typewriting machine, a traveling spring-driven platen carriage, a toothed escapement member normally driven in one direction from the carriage, a dog rocker pivotally supported independently of the carriage, escapement dogs on said rocker, a return spring connected with the dog rocker, stopping means for arresting return movement of the dog rocker, tappet means for actuating the dog rocker against the resistance of its return spring, a stop member pivotally supported independently of the dog rocker and normally spaced therefrom and engageable by the rocker upon actuation of said tappet means, a spring connected with the pivoted stop member and yieldably holding the same in position to prevent overthrow of the rocker when the tappet means is actuated, and overthrow-preventing means for limiting the extent of dog-rocker-actuating movement of said tappet means.

37. In a typewriting machine escapement, a dog rocker and an overthrow-preventing stop member therefor pivotally supported to rock about parallel axes, a return spring for the dog rocker, a spring connected with said stop member to yieldably hold the same against movement by the dog rocker, means for limiting movement of the stop member by the spring to determine a normal stop-

ping position of said member in which said member is out of contact with the dog rocker when the dog rocker is in its returned position, and tappet means for rocking the dog rocker against the action of its return spring toward said stop member.

38. In a typewriting machine escapement, a dog rocker and an overthrow-preventing stop member therefor pivotally supported to rock about parallel axes, a return spring for the dog rocker, a spring connected with said stop member to yieldably hold the same against movement by the dog rocker, means for limiting movement of the stop member by its connected spring to determine a normal stopping position of said member in which said member is out of contact with the dog rocker when the dog rocker is in its returned position, tappet means for rocking the dog rocker against the action of its return spring toward said stop member, and an overthrow-preventing stop for said tappet means.

39. In a typewriting machine escapement, a dog rocker and an overthrow-preventing stop member therefor pivotally supported to rock about parallel axes, a return spring for the dog rocker, a spring connected with said stop member to yieldably hold the same against movement by the dog rocker, means for limiting movement of the stop member by its connected spring to determine a normal stopping position of said member in which said member is out of contact with the dog rocker when the dog rocker is in its returned position, tappet means for rocking the dog rocker against the action of its return spring toward said stop member, and hand-operable escapement-releasing means effective on said pivoted stop member to rock the same against the resistance of its connected spring, said member having a part engageable with the dog rocker to effect a release of the escapement by an excessive rocking movement of said rocker against the action of the rocker return spring upon actuation of said releasing means.

40. In an escapement mechanism, a vibratory dog carrier having two parts spaced in the direction of motion of the carrier, a shiftable member extending between said spaced parts and normally cooperating with one of said parts to prevent overthrow of the carrier, and hand-operable means arranged to shift said member from its normal position at will, said member when shifted by said hand-operable means cooperating with the other of said spaced parts of the dog carrier to overthrow the carrier and thereby release the escapement.

41. In an escapement mechanism, a toothed member normally urged in one direction, escapement dogs cooperative with said member, a vibratory carrier for the dogs, a member having a part thereof normally engage-

able by the carrier to limit movement of the carrier in one direction to prevent accidental release of the escapement by an overthrow of the carrier and a part thereof engageable 5 with the carrier to move the carrier in said direction to overthrow the carrier, hand-operable escapement-releasing means associated with said member to shift the member to render said first mentioned part ineffective on 10 the carrier and the second part effective on the carrier to shift the carrier to an overthrown position in which the toothed member is free from the control of said dogs, and means normally holding said member in its 15 position for preventing overthrow of the carrier.

42. In a typewriting machine, a spring-driven platen carriage, a toothed member driven with the carriage, a vibratory dog 20 carrier mounted independently of the carriage having two parts spaced in the direction of motion of the carrier, escapement dogs on said carrier cooperative with said toothed member, a shiftable member supported independently of the carriage extending 25 between said spaced parts of the dog carrier and normally cooperating with one of said parts to prevent overthrow of the carrier, and hand-operable means mounted on 30 the carriage to travel therewith and engageable with said shiftable member in all positions of the carriage adapted to shift said member from its normal position, said shiftable member when shifted by said hand-operable means cooperating with the other of 35 said spaced parts on the dog carrier to overthrow the carrier and thereby free the toothed member from the control of said dogs.

43. In an escapement mechanism, a sheet metal dog carrier having a flat body part formed with integral pendent pivot ears at its ends and an integral holding dog at one edge thereof, one of said ears having formed 45 thereon an integral stop arm extending above the plane of the body part of the rocker and an integral pendent arm lying flatwise in the plane of said ear and having its lower end bent up at a right angle thereto to form a contact lug for engagement by an operating tappet.

44. In an escapement mechanism, a sheet metal dog carrier having a flat body part formed with integral pendent pivot ears at its ends and an integral holding dog at one edge 55 thereof, one of said ears having formed thereon an integral stop arm extending above the plane of the body part of the rocker and an integral pendent arm lying flatwise in the plane 60 of said ear and having its lower end bent up at a right angle thereto to form a contact lug for engagement by an operating tappet, the other pivot ear having an integral lug extending laterally from its lower end and pierced

for attachment of a carrier return spring 65 thereto.

45. In a typewriting machine, a traveling carriage spring-driven in one direction, a carriage support, a sheet metal bracket having a flat body part held to said support and provided with pendent side members, a rack held to the carriage, a shaft journaled on the bracket and extending through the flat body part thereof, a feed pinion fixed on the upper end of said shaft meshing with said rack, an escapement wheel fixed on the lower end of said shaft, a sheet metal dog rocker having a flat body part formed with pendent pierced pivot ears at its ends, pivot screws for said rocker threaded through said members of the bracket and having bearing portions engaged 70 in the apertures in said rocker ears, an integral holding dog projecting from one edge of the body part of the rocker, a feeding dog projecting from the same edge of the rocker, a pivot screw for said dog threaded into the flat body part of the rocker, one of the pivot ears of said rocker having an integral stop arm normally engaged with said bracket to limit upward swinging of the rocker and an integral pendent arm, a rocker return spring connecting the other rocker pivot ear with 75 said bracket to yieldably hold said stop arm normally engaged with the bracket, and means for rocking the rocker downward 80 through the medium of said pendent arm.

46. In an escapement, a sheet metal dog carrier having a flat body part and pivot ears at an angle to said body part, a holding dog formed integrally with said body part, a sheet metal feeding dog having a pair of laterally extending arms at opposite sides thereof, a pivot screw extending through the feed dog and threaded into the body part of the carrier, a pair of sheet metal levers, pivot screws extending through said levers and threaded into the body part of said carrier at opposite sides of the feeding dog, said levers having inwardly extending arms and arms at an angle to the inwardly extending arms, a tension spring connecting the last-mentioned lever arms and urging the inwardly extending lever arms toward the laterally extending feeding-dog arms, and a pair of integral stops formed on the body part of the dog carrier 105 engaged by said levers to limit movement of the levers by the spring, said inwardly extending lever arms engaging the feeding dog arms to yieldably resist movement of the feed dog in both directions about its pivot when the levers are engaged with said stops.

47. In a typewriting machine, a shift frame, a shift key connected to shift said frame, a platen carriage shiftable with the shift frame, escapement mechanism or the carriage shiftable with the shift frame and including a pivoted dog carrier, a pivoted member shiftable with the shift frame and

normally yieldably held in position to cooperate with the dog carried to prevent overthrow of the carrier, and tappet means on the main frame for actuating the carrier.

5 48. In a typewriting machine, a shift frame, a shift key connected to shift said frame, a platen carriage shiftable with the shift frame, escapement mechanism for the carriage shiftable with the shift frame and including a pivoted dog carrier, a pivoted member shiftable with the shift frame and normally yieldable held in position to cooperate with the dog carrier to prevent overthrow of the carrier, tappet means on the main frame 10 for actuating the carrier, and manually operable means on the carriage for rocking said pivoted member out of its normal position, said member when so rocked being adapted to engage and overthrow the dog carrier to release the escapement.

20 49. In an escapement mechanism, the combination of a toothed member normally urged

in one direction, a vibratable dog carrier, dogs on said carrier cooperative with the toothed member to effect a step-by-step movement of the toothed member under the influence of its driving means when the dog carrier is vibrated, a shiftable overthrow stop, means yieldably holding said stop normally in position to block overthrow of the dog carrier in one direction during feed-controlling vibrations of the carrier, and means whereby said stop may be shifted at will in opposition to said yieldable means to cause the stop to overthrow the carrier beyond its normal point of arrest by the stop to a position in which the toothed member is free from control of the dogs.

In testimony whereof we hereunto affix our signatures.

HENRY ALLEN AVERY.

OTTO PETERMANN.

EDWIN L. HARMON.
